UNITED STATES PATENT OFFICE.

FREDERICK J. BACON AND DAVID L. DAY, OF GROTON, CONNECTICUT.

SNARE DRUM.

Application filed August 27, 1925. Serial No. 52,860.

The present invention has for its primary object to provide, in connection with a snare drum, novel means for amplifying and improving the tone qualities of the instrument.

The ordinary snare drum is somewhat lacking in tone volume and staccato qualities even though the vellum batter and snare heads thereof be properly and carefully tensioned as also the snares, and even experienced drummers frequently find difficulty in producing a close and uniform roll in playing the instrument. Therefore, the present invention has as its object to provide in connection with a snare drum, a resonator which will serve to amplify the sound vibrations, thus greatly enhancing the tone qualities of the instrument and enabling the player to play the instrument with a more pleasing effect than has heretofore been possible.

The principles of the invention may find embodiment directly in the construction of a snare drum but, in its more specific aspect, the invention contemplates the provision of a resonator or amplifier attachment for such an instrument which may be readily applied thereto and which will effectually serve the purposes outlined above.

In the accompanying drawings:

Figure 1 is a perspective view of a snare drum embodying the present invention.

Figure 2 is a vertical sectional view taken substantially on the line 2—2 of Figure 1, looking in the direction indicated by the arrows.

As illustrated in the drawings, the drum in itself comprises the usual cylindrical shell or body 1, which may be of wood or metal, and over the forward side of which is stretched the usual vellum 2 constituting the batter head of the drum, the numeral 3 indicating the usual wood tensioning ring which is fitted over the said front of the shell body and coacts with the usual ring 4 about which the marginal portion of the vellum 2 is bound, the ring 3 being rabbeted as at 5, and having fitted thereto the metal tensioning hoop or ring 6 with which are engaged the usual tensioning hooks 7. The numeral 8 indicates the vellum which is stretched over the rear side of the shell or body 1 and constitutes the snare head of the drum and is tensioned by the usual wood ring or hoop 9 which coacts with the metal ring 10 about which the marginal portion of the vellum 8 is bound, the usual metal tensioning ring

11 being fitted in a rabbet 12 formed circumferentially in the outer side of the hoop or ring 9 and being engaged by the usual tensioning hooks 13. The snares are indicated by the numeral 14 and, as usual, extend diametrically across and substantially in contact with the snare head 8. The construction so far described is representative of the ordinary snare drum that in the specific embodiment of the invention illustrated in the drawings and, for a purpose to be presently described, the rabbeted portion of the ring 9 is of somewhat greater depth than usual so as to provide an extended portion 15 projecting beyond the rear edge of the ring 11.

As previously stated, the invention resides generally in the provision of an amplifier or resonator which is indicated in general by the numeral 16, and the same comprises an outwardly bulged head 17 which is preferably of wood, although metal may be employed for the purpose. Where the head 17 is made of wood, it is preferably gradually decreased in thickness from its peripheral portion to its central portion and, therefore, possesses resonant qualities. The amplifier or resonator further comprises an annular shell which is indicated in general by the numeral 18 and which is preferably of metal and integral throughout and this annular shell embodies a cylindrical attaching flange 19 which is fitted to the exterior of the extension 15 of the ring 9 and secured in place by screws 20 which are threaded through bosses 21 formed upon the outer side of the flange and engaged in openings 22 formed in the said extension 15 of the ring 9, the screws being provided with knurled heads 23 whereby they may be conveniently rotated manually in applying and removing the amplifier or resonator. From the flange 19, the annular shell 18 is flared outwardly and rearwardly, as indicated by the numeral 24, and the rear peripheral portion thereof seats in a rabbet 25 extending circumferentially of the periphery of the head 16, securing screws 26 being fitted through this portion of the annular shell and threaded into the said peripheral portion of the head. The outwardly and rearwardly flared portion of the annular shell is formed with a number of openings 27 which provide for the escape of the sound waves from the resonating cham-

ber which is defined by the snare head 8, the head 16, and the annular shell 18.

It will be evident from the foregoing description of the invention that the sound waves propagated through vibration of the snare head or vellum 8 and the snares 14 will be amplified within the amplifying or resonating chamber through reverberation, due to the resonant character of the head 16, and due to reverberation, the vibration of the snares 14 as well as the vibration of the vellum 8 will be prolonged and amplified, thereby amplifying the sound waves and greatly improving the tone quality thereof.

In the specific embodiment of the invention illustrated in the drawings the invention is disclosed as an attachment for snare drums, but it will be quite evident that the invention may find embodiment directly in the construction of the drum itself and that the resonating and amplifying chamber may be constructed otherwise than as specifically illustrated and described, without in any way departing from the spirit of the invention.

Having thus described the invention, what we claim is:

1. The combination with a snare drum embodying the usual batter and snare heads,

of a resonating and amplifying chamber enclosing the said snare head. 30

2. The combination with a snare drum embodying the usual batter and snare heads, of an enclosed resonant member confronting the said snare head. 35

3. The combination with a snare drum embodying the usual batter and snare heads, the last mentioned head including the usual vellum-tensioning ring, of a resonating and amplifying chamber comprising a head of resonant material and an annular shell surrounding and supporting the head and, in turn, supported by the said tensioning ring. 40

4. The combination with a snare drum embodying the usual batter and snare heads, 45 of an amplifying chamber comprising a resonant wall attached to and surrounding the snare head, and a resonant head supported by said resonant wall and opposing the said snare head, the resonant wall, 50 resonant head and snare defining a resonating chamber housing the snares, and the wall having sound outlet openings therethrough.

In testimony whereof we affix our signatures.

FREDERICK J. BACON. [L. S.]
DAVID L. DAY. [L. S.]
